EXTRUDING PRESS

Samon H. Stupakoff, Latrobe, and Rawson E. Stark, Greensburg, Pa., assignors to Stupakoff Ceramic & Manufacturing Company, Latrobe, Pa., a corporation of Pennsylvania

Application September 5, 1942, Serial No. 457,416

10 Claims. (Cl. 25—16)

This invention pertains to the art of extruding ceramic and similar mixes into the form of rods, tubes or other shapes, and our invention relates particularly to an apparatus for such extrusion designed to eliminate defects due to the presence of entrapped air in the material which is being extruded.

In the practice of extruding materials of this nature, as for example ceramic mixes to be used in the manufacture of high grade insulators to be used in radio equipment, a relatively dry mix is charged into the open end of a cylinder, the axis of which is vertical. At the bottom of the cylinder is a die. A ram forces a piston down into the top of this cylinder compressing the mix within the cylinder and forcing it out through the opening in the die at the bottom of the cylinder. As the material emerges from the die it hangs in suspension. After it has reached a predetermined length and usually before it contacts the base of the press, it is removed and a new length of material is likewise extruded. It is important that the material be compacted under considerable pressure in order that it will have the desired density. It is also important that it be free of air bubbles and that it be straight as it hangs from the die.

Heretofore a considerable amount of extruded material was defective due to the inclusion of air and air bubbles in the mix. Frequently a bubble of air under several thousand pounds of pressure per square inch would, when the material emerged from the die, expand with a loud report and rupture the material being extruded. Lesser amounts of air will produce small fissures, voids and irregularities in the material. Various attempts have been made to eliminate this difficulty but, so far as we know, such attempts have been unsuccessful.

According to the present invention, the loose material is charged into the extrusion chamber or cylinder in batches, and after each batch the air is evacuated and the material is compacted while it remains under vacuum. Thereafter the compacted material is placed under vacuum and most of the residual air is withdrawn and then, before the seal to the air is broken, the extruding operation is commenced and air is prevented from getting back into the cylinder during such extrusion. The invention is preferably embodied in a press of more or less conventional type having two cylinders which may alternately be brought to position under the extrusion ram. During the time that one cylinder is in position for the material to be ex-

truded therefrom, the other cylinder is in a position where the batch of material may be charged into it. According to our invention, vacuum cups are arranged to be positioned over the ends of both cylinders so that the contents of each cylinder may be evacuated to a predetermined extent, as will hereinafter more fully appear.

Our invention may be readily understood by reference to the accompanying drawing in which

Figure 1 is a side elevation of a press embodying our invention, certain parts thereof being shown in section;

Figure 2 is a transverse horizontal section in substantially the plane of line II—II of Figure 1.

In the drawing 2 and 3 are parallel columns supported on pedestals 4 carried on a base member 4a. At the top of these columns is supported a hydraulic cylinder 5 having a piston 6 with a plunger 7 on the lower end thereof.

Mounted on the column 2 is a sleeve 8 which has two similar arms 9 and 10. Each arm carries a cylinder, these cylinders being designated 11 and 12. The two cylinders are preferably of the same length and are of the same diameter. When the cylinder 12 is under the plunger 7 the cylinder 11 projects to one side of the frame of the press where it is in a position to receive a charge. When the charge in

the cylinder 12 has been exhausted, the assembly comprising the sleeve 8 and the arms 9 and the cylinders 11 and 12 are rotated 180° to bring the cylinder 11 under the plunger 7 and move the cylinder 12 to the charging position. The

assembly can rotate only 180°, there being hook-like extensions 13 projecting outwardly from the side of each cylinder. These hook-like extensions alternately engage the column 3, the column 3 being provided with abutments 14 be-

tween which extensions engage and which provide a support for the swinging end of the assembly. This general arrangement of two cylinders pivotally supported is now generally known to the art and this per se forms no part

of the present invention. Each cylinder 11 and 12 has a shouldered opening in the bottom thereof, and a die or die adapter 15 is set into the bottom of each cylinder. Under the tremendous pressure which is used for extruding the material some of the material will sometimes wedge in around the periphery of the member 15, due in many cases to the cylinder wall being sprung outwardly very slightly under pressure. When the material becomes wedged around the member 15 it is very difficult to re-

move the member 15. An incidental feature of the present invention provides for the removal of the dies or die adapter 15 when they become so wedged.

On the piston rod 6 of the main ram is an inverted cup member 16 which has a flange 17 at the bottom thereof and set into this flange is a rubber or other suitable gasket 18. The cup is provided with a gland 19 at the top thereof which provides a sliding fluid-type seal about the piston rod 6. A nipple 20 opening into the cup 16 is connected through flexible tubing (not shown) with a vacuum pump (not shown). Compression springs 16a tend to urge the cup downwardly while the plunger 7 on the piston rod 6 provides a means for raising this cup.

In operation, when a cylinder is first brought to position under the plunger 1 the plunger 7 is lowered slightly and the springs 16a force the gasket 18 on the cup 16 into sealing contact with the top of the cylinder 12. This seal is made before the plunger 7 actually enters the cylinder. Before the operation is further proceeded with the space within the cup 16 is evacuated and all removable air which remains in the charge in the cylinder is withdrawn. A vacuum gauge in the line to the vacuum pump may be provided to indicate to the operator when the desired amount of air has been removed.

Mounted on the column 3 below the extrusion die of the press is a sleeve 22 having an arm 23 projecting therefrom. At the outer end of this arm is an adjusting screw 24 having a hand wheel 25. Supported at the top of the screw 24 is a cup member 26 generally similar to the cup member 16, except that the cup 26 is swiveled at the top of the screw 24 instead of there being a gland; the swiveled connection being indicated at 26a.

The sleeve 22 may be rotated about the column 3 to move the cup 26 from the position shown in full lines in Figure 1 to the position shown in dotted lines. In the latter position the cup projects to one side of the press and is out of the way of the material which is being extruded and out of the way of the operator. This cup, like the cup 16, is provided with a nipple 26b that is connected through a flexible tubing (not shown) with a vacuum pump.

In operation, the cup 26 is swung to a position below the extrusion die before the extruding operation has commenced, and the screw 24 is turned to elevate the cup 26 and seal it against the bottom of the cylinder 12. At the same time that air is being withdrawn from the charge at the top of the cylinder, air is also being withdrawn from the charge through the cup 26. When the vacuum gauge indicates that a substantially constant degree of vacuum is being held by the cups 16 and 26, and hence that no more air is being released from the charge, the plunger 6 is started down, forcing some of the contents of the cylinder through the die into the cup 26. The motion of the plunger 6 is then stopped; the cup 26 is backed down and the cup 26 is then swung to the dotted line position shown in Figure 1 and the extruding operation is then continued. By forcing some of the charge into the cup 26 before removing the cup the discharge end of the die is plugged by extruded material. Air will not enter through the die to any considerable extent before the extruding operation is started and of course while the material is being forced out under several thou-

sand pounds of pressure the air can not flow back through the die.

Quite as important as the exhausting of the air from the cylinder 12 which is before the pressing operation starts, is the provision made for removing most of the air from the mix at the charging station. For this purpose a hydraulic ram 27 having a plunger 28 is mounted on one side of the upper part of the press in such position that the plunger 28 can be entered into the cylinder 11 which is at the charging station. Associated with the plunger 28 is a vacuum cup assembly 29 similar to the cup 16. It has a compressible gasket 29a, and on its lower face a nipple 29b for connection with a vacuum line, and a gland 26c.

Mounted on the column 2, directly under and in line with the line 21, is another hydraulic ram 30, having a piston rod 31 at the top of which is removably carried a vacuum cup assembly 32 which is substantially similar to the vacuum cup 26 and which has a nipple 33 for connection with the vacuum line (not shown).

In operation, the ceramic mix which is of a granular character and which ordinarily contains only a very small amount of water, the operation usually being a so-called extrusion operation, the vacuum cup 32 is elevated to engage the bottom of the cylinder 11. An amount of the ceramic mix is charged into the cylinder at the charging station. When a predetermined amount of material has been charged into the cylinder at the charging station the ram 27 is operated to bring the cup 29 into engagement with the top of the cylinder in the charging station. Before the plunger 28 enters the cylinder, vacuum may be applied to cup 29 and cup 32 and the loose, granular material in the cylinder can be partially de-aerated. Then the plunger 28 is forced down to compact the loose material after which the ram 27 is operated to open the top of the cylinder, additional material is charged into the cylinder and the cycle repeated on this second batch of charge. Succeeding smaller batches may be added in like manner. It will thus be seen that successive batches are separately introduced into the cylinder and air evacuated therefrom.

During the time that the charge between the cups 16 and 26 is being evacuated the completed charge in the cylinder at the charging station between the cups 29 and 32 is also being evacuated and the vacuum is held on this charge while the material is being extruded from the main ram. Consequently, most of the air is removed from the material at the charging station and when one cylinder has been emptied the other cylinder is immediately swung to position under the extruding ram. Some air of course will enter the compacted charge as the cylinder is swung from the charging to the extruding position, but this air is removed by the evacuating stage applied throughout cups 16 and 26 and before the extrusion charge begins.

The operation thus described very substantially removes entrapped air from the mix and a superior product is uniformly procured. The invention has very substantially reduced the amount of defective or scrap material.

When it is necessary to remove one of the dies or die-adapters 15, and this member has become wedged in the cylinder, as hereinbefore described, the vacuum cup 32 may be lifted from the top of the plunger 31. Pressure may then be applied to the cylinder 30 to force this ram

upwardly and the ram 30 thus provides a hydraulic jack for loosening and lifting the die member 15.

While any suitable source of water pressure may be employed for operating the several rams, it is preferable to provide two pumps for operating the main ram. The pump 35 is a low pressure pump of large capacity and the second pump 36 delivers a small volume of water at very high pressure. For example, the low pressure pump may produce up to 500 lb. per square inch of pressure, whereas the high pressure pump may produce a pressure of around 2000 or 3000 lb. per square inch. A check valve 37 prevents the high pressure water from going into the low pressure pump. The reason for using two pumps is that in initially moving the plunger and compacting the charge to be extruded, the rate of movement of the ram 6 is quite fast, so that a large amount of water is required. After this initial compacting operation, however, the plunger moves very slowly and considerable pressure is required. Hence, a very small capacity high pressure pump is used. Both pumps operate continuously and the output of each may be bypassed. According to the present invention, the low pressure pump is additionally connected with the cylinders 27 and 30 as indicated by the dot and dash lines in Figure 1, providing a source of power for these cylinders. The cylinders 27 and 30 may thus be operated with low pressure water while the high pressure water is being used in the main ram 5 for extruding material. This arrangement conserves pump capacity and saves energy.

Our invention provides a method and apparatus according to which most of the air may be effectively eliminated from the material being extruded in a conventional extrusion press. Our invention contemplates a pre-deaeration of the material in the charging station and a final deaeration at the extruding station, and it also provides against the re-entrance of air into the charge once the material is ready to be extruded.

While we have illustrated and described one particular apparatus for carrying out our invention and have outlined one preferred procedure in practicing our method, it may be understood that various changes and modifications may be made within the contemplation of our invention and under the scope of the following claims.

We claim:

1. Apparatus for extruding ceramic and the like mixes comprising a press having a charge holding cylinder and a ram operable in the cylinder for forcing ceramic material from one end of the cylinder, and means at each end of the cylinder movable into and out of engagement with that end of the cylinder adjacent which it is located for withdrawing air from the charge within the cylinder, said means having a sealing surface thereon for contacting the end of the cylinder with which it cooperates.

2. Apparatus for the extrusion of ceramic and the like mixes comprising a press having a charge holding cylinder, a ram cooperating with the cylinder for ejecting the charge therefrom, said ram being adapted to enter one end of the cylinder, the cylinder having an extrusion die at the other end thereof, and a cover member at each end of and outside the cylinder movable into and out of engagement with that end of the cylinder adjacent which it is located for temporarily clos-

ing the ends of the cylinder, and connections leading from the interior of said cover members to a vacuum pump.

3. Apparatus for the extrusion of ceramic and the like mixes comprising a press having a charge holding cylinder, a ram cooperating with the cylinder for ejecting the charge therefrom, said ram being adapted to enter one end of the cylinder, the cylinder having a die at the other end thereof, and a cover member movable into and out of engagement with each end of the cylinder for temporarily closing the ends of the cylinder, and connections leading from the interior of said cover members to a vacuum pump, the cover member at one end of the cylinder surrounding said ram and being sealed about the ram.

4. Apparatus for the extrusion of ceramic and the like mixes comprising a press having a charge holding cylinder, a ram cooperating with the cylinder for ejecting the charge therefrom, said ram being adapted to enter one end of the cylinder, the cylinder having a die at the other end thereof, and a cover member movable into and out of engagement with each end of the cylinder for temporarily closing the ends of the cylinder, and connections leading from the interior of said cover members to a vacuum pump, the cover member at the die end of the cylinder being movable both axially of the cylinder and transversely with respect thereto.

5. Apparatus for extruding ceramic and the like mixes comprising a press having a cylinder, a ram which enters the cylinder at one end thereof, the other end of the cylinder being provided with a die, a cover member about the ram adapted to be brought into sealing relation with the end of the cylinder into which the ram enters, and a second cover member at the die end of the cylinder movable axially into and out of engagement with the die end of the cylinder, said cover members having connections through which they may be connected to a vacuum pump whereby the charge end of the cylinder may be evacuated.

6. Apparatus for extruding ceramic and the like mixes comprising a press having a charge containing cylinder, said cylinder being movable from a charging position to an extruding position, a ram on the press which enters one end of the cylinder at the charging position for compacting the charge in the cylinder, a second ram on the press positioned to enter one end of the cylinder and expel the charge therefrom when the cylinder is in the extruding position, and means for evacuating air from both ends of the charge in the cylinder in both positions.

7. Apparatus for extruding ceramic and the like mixes comprising a press having a charge containing cylinder, said cylinder being movable from a charging position to an extruding position, a ram on the press which enters one end of the cylinder at the charging position for compacting the charge in the cylinder, a second ram on the press positioned to enter one end of the cylinder and expel the charge therefrom when the cylinder is in the extruding position, cover members about both of said rams movable with the rams into and out of sealing engagement with one end of the cylinder, and movable cover members on the press movable into and out of engagement with the other end of the cylinder, one engaging the cylinder in the charging position and one engaging the cylinder in the extruding position, all of said cover members having connections adapted to be connected with a vacuum pump.

8. Apparatus for extruding ceramic and the

like mixes comprising a press having a charge containing cylinder, said cylinder being movable from a charging to an extruding position, a ram on the press which enters one end of the cylinder at the charging position for compacting the charge in the cylinder, a second ram on the press positioned to enter one end of the cylinder and expel the charge therefrom when the cylinder is in the extruding position, the cylinder having a die at the other end thereof, cover members about both of said rams movable with the rams into and out of sealing engagement with one end of the cylinder, and movable cover members on the press movable into and out of engagement with the other end of the cylinder, one engaging the cylinder in the charging position and one engaging the cylinder in the extruding position, all of said cover members having connections adapted to be connected with a vacuum pump, the cover member which engages the die end of the cylinder in the extruding position being movable both axially and transversely with respect to the cylinder.

9. Apparatus for extruding ceramic and the like mixes comprising a press having a charge containing cylinder, said cylinder being movable from a charging position to an extruding position, a ram on the press which enters one end of the cylinder at the charging position for compacting the charge in the cylinder, a second ram on the press positioned to enter one end of the cylinder and expel the charge therefrom when the cylinder is in the extruding position, the cylinder having a die at the other end thereof, cover members about both of said rams movable with the rams into and out of sealing engagement with one end of the cylinder, movable cover members on the press movable into and out of engagement with the die end of the cylinder, one

engaging the cylinder in the charging position and one engaging the cylinder in the extruding position, all of said cover members having connections adapted to be connected with a vacuum pump, and a ram mounted on the press for supporting the cover member which engages the die end of the cylinder in the charging position for moving the cover member axially of the cylinder into and out of engagement therewith.

10. Apparatus for extruding ceramic and the like mixes comprising a press having a charge containing cylinder, said cylinder being movable from a charging position to an extruding position, a ram on the press which enters one end of the cylinder at the charging position for compacting the charge in the cylinder, a second ram on the press positioned to enter one end of the cylinder and expel the charge therefrom when the cylinder is in extruded position, the cylinder having a die at the other end thereof, cover members about both of said rams movable with the rams into and out of sealing engagement with one end of the cylinder, movable cover members on the press movable into and out of engagement with the die end of the cylinder, one engaging the cylinder in the charging position and one engaging the cylinder in the extruding position, all of said cover members having connections adapted to be connected with a vacuum pump, and a ram mounted on the press for supporting the cover member which engages the die end of the cylinder in the charging position for moving the cover member axially of the cylinder into and out of engagement therewith, the cover member on said last named ram being removably secured to the ram whereby the ram may be used to press against the die in the die end of the cylinder.
